US00D901095S

(12) **United States Design Patent** (10) **Patent No.:** **US D901,095 S**
MacNeil et al. (45) **Date of Patent:** **** Nov. 3, 2020**

(54) **SINGLE-BOWL PET WATER/FOOD STATION**(71) Applicant: **MACNEIL IP LLC**, Bolingbrook, IL (US)(72) Inventors: **David F. MacNeil**, Fort Lauderdale, FL (US); **Frederick W. Masanek, Jr.**, Barrington, IL (US)(73) Assignee: **MACNEIL IP LLC**, Bolingbrook, IL (US)(**) Term: **15 Years**(21) Appl. No.: **29/732,484**(22) Filed: **Apr. 24, 2020****Related U.S. Application Data**

(60) Division of application No. 29/635,541, filed on Jan. 31, 2018, which is a continuation-in-part of application No. 29/621,052, filed on Oct. 4, 2017, now Pat. No. Des. 887,650, which is a continuation-in-part of application No. 29/602,916, filed on May 4, 2017, now Pat. No. Des. 873,503, which is a continuation-in-part of application No. 29/560,208, filed on Apr. 4, 2016, now Pat. No. Des. 802,853.
